PISTON-RING CONSTRUCTION

Hsia-Si Pien, Waltham, Mass., assignor to Wilkening Manufacturing Co., Philadelphia, Pa., a corporation of Delaware

Original application January 22, 1954, Serial No. 405,565, now Patent No. 2,777,740, dated January 15, 1957. Divided and this application September 13, 1956, Serial No. 610,051

2 Claims. (Cl. 309—44)

The present invention relates to certain new and useful 3-piece piston-rings for internal combustion engines and the like and to a novel spacer-and-expander for such type piston-rings.

There has been a long-felt need for non-bottoming, self-expanding piston-rings, namely piston-rings which exert an expansive force irrespective of whether or not the piston-ring is in contact with the bottom of the ring-receiving groove, and which effect a uniform circumferential engagement of the piston-ring sealers or rails against the cylinder walls.

Recently a number of such non-bottoming circumferentially expandable piston-rings have been developed which have achieved a more or less satisfactory level of performance. However by and large such self-expanding piston-rings have been of relatively complex construction and have required a large amount of bending and milling in their fabrication. Moreover, due to their structural complexity such heretofore developed piston-rings have in some instances developed poor performance characteristics after a period of use, with the spacer-and-expander portion of the piston-ring becoming deformed and causing malfunction.

This invention has as an object the provision of a non-bottoming circumferentially expandable piston-ring which does not require any support and is capable of functioning for greatly protracted periods in a highly satisfactory manner.

Another object of the present invention is a piston-ring which will conform to the cylinder-wall notwithstanding any slight out-of-roundness or out-of-cylindrical shape of the cylinder-wall due either to distortion of the cylinder-wall or due to wear, and one which will "break in" readily.

Another object of the present invention is a piston-ring which will bear against the cylinder-wall with uniform or equalized outward radial pressure and which will effectively seal against the cylinder-wall and which may have a relatively high unit of contact-pressure per unit of contact-area with the cylinder-wall, and which will provide adequate lubrication with good oil control.

For the purpose of illustrating the invention, there are shown in the accompanying drawings one form thereof, although it is to be understood that the various instrumentalities of which the invention consists can be variously arranged and organized and that the invention is not limited to the precise arrangements and organizations of the instrumentalities as herein shown and described.

In the accompanying drawings in which like reference characters indicate like parts:

Figure 1 is an "exploded" perspective view of a composite 3-piece piston-ring representing one embodiment of the present invention.

Figure 2 represents a side sectional view of the same, in position in the ring-receiving groove of a piston, with the sealing-rings of the piston-ring contacting the cylinder-wall.

Figure 3 is a plan view of a fragmentary portion of a cut strip of band or ribbon of flat spring metal, such as

2

spring-steel, from which the spacer-and-expander of the three-piece piston-ring of the present invention is formed, showing the first stage in the formation of the spacer-and-expander.

Referring to Figures 1 and 2 for one embodiment of the piston-ring of the present invention, the piston-ring shown therein comprises an upper or top thin flat sealing-ring, oil-scraper or oil-control ring element 20, a bottom or lower sealing-ring, oil-scraper or oil-control ring element 21, and a spacer-and-expander designated 66, comprising a continuous radially corrugated circumferentially compressible and expandable ring having its ends 72 abutting each other when the spacer-and-expander is operatively positioned. The operative position of the spacer-and-expander is shown in Figure 1 where ends 77 are abutting.

The spacer-and-expander 66 comprises an axially and radially corrugated flat band of spring metal having spacer tabs 68 and rail-engaging tabs 70, the latter being axial extensions of the radial innermost portions 69 of spacer-and-expander 66. In the embodiment shown in the drawings, three spacer tabs 68 are provided intermediate each two rail-engaging tabs 70. Spacer tabs 68 project axially outwardly from the body of spacer-and-expander 66 for a smaller distance than rail-engaging tabs 70. As seen in Figure 1, a spacer tab 68 is provided at the radially outward extremity of each of the radial corrugation, with a spacer tab 68 intermediate said radially outwardly disposed spacer tab and the rail-engaging tab 70; with the outer axial surface or end 73 of each spacer tab 68 serving as a seating surface for rails 20 and 21.

The free ends 72 of spacer-and-expander 66 abut when spacer-and-expander 66 is operatively positioned (as shown in Figure 1). The spaces between adjacent the tabs 68 and 70 provide oil passageways. If desired, the spacer-and-expander 66 may be slotted or perforated by axially spaced slots or holes to provide additional oil passageways.

The spacer-and-expander 66 is milled or punched from a flat band (see Figure 3) to form the rail-engaging 40 tongues or tabs 70 positioned at regularly spaced intervals on both margins, with a plurality (in the embodiment shown, three) of spacer tabs 68 therebetween, and is then radially corrugated and convoluted to form a finished spacer-and-expander.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having described the invention, the following is claimed:

1. A composite 3-piece non-bottoming piston-ring 55 adapted to be confined within the ring-receiving groove of a piston comprising a pair of parallel-spaced sealing-rings adapted to be disposed closely adjacent the sidewalls of said ring-receiving groove, a non-bottoming radially-corrugated circumferentially-expanding spring-metal spacer-and-expander disposed between said pair of sealing-rings with its ends abutting each other and with such abutment causing the spacer-and-expander to resist circumferential compression when compressed by the sealing rings when mounted in the cylinder, said spacer-and-expander comprising a radially corrugated band, a plurality of radially-outwardly disposed sealing-ring seating tabs on and extending axially from each of the two opposite edges of each of said corrugations, with the axially outermost surface of said seating tabs comprising supporting surfaces on which the sealing-rings are seated and constituting the sole axial spacing means between said

sealing rings, said plurality of seating tabs providing axial support for said sealing-ring both along a zone near the outermost periphery thereof as well as along a zone spaced substantially inwardly from said first-mentioned zone, radially-thrusting ring-engaging tabs on the radially innermost portion of said spacer-and-expander having greater axial length than said seating tabs, the radially-outward surface of said radially thrusting ring-engaging tabs overlapping and engaging the inner peripheral edges of the sealing-rings, said sealing-rings and spacer-and-expander being so constructed and arranged that when the sealing-rings are collapsed to cylinder diameter and confined within the side-walls of said ring-receiving groove with the spacer-and-expander disposed between them and the aforesaid radially thrusting ring-engaging tabs engaged with the inner peripheral edges of said sealing-rings, the spacer-and-expander will be compressed circumferentially and will urge the sealing-rings outwardly by means of the aforesaid ring-engaging surfaces of said radially-thrusting ring-engaging tabs.

2. A composite 3-piece non-bottoming piston-ring adapted to be confined within the ring-receiving groove of a piston comprising a pair of parallel-spaced sealing-rings adapted to be disposed closely adjacent the side-walls of said ring-receiving groove, a non-bottoming radially-corrugated circumferentially-expanding spring-metal spacer-and-expander disposed between said pair of sealing-rings with its ends abutting each other and with such abutment causing the spacer-and-expander to resist circumferential compression when compressed by the sealing rings when mounted in the cylinder, said spacer-and-expander comprising a radially corrugated band hav-

ing radially-outwardly disposed sealing-ring-seating and supporting tabs on which the sealing-rings are seated axially and constituting the sole axial spacing means between said sealing rings, and providing axial seating and support for said sealing-rings both in a zone near the outermost periphery thereof as well as in a zone near the inner periphery thereof, radially-thrusting ring-engaging tabs on the radially innermost portion of said spacer-and-expander having greater axial length than said seating tabs, the radially-outward surface of said radially-thrusting ring-engaging tabs overlapping and engaging the inner peripheral edges of the sealing-rings, oil-passageways for removing oil through said piston-ring, said sealing-rings and spacer-and-expander being so constructed and arranged that when the sealing-rings are collapsed to cylinder diameter and confined within the side-walls of said ring-receiving groove with the spacer-and-expander disposed between them and the aforesaid radially-thrusting ring-engaging tabs engaged with the inner peripheral edges of said sealing-rings, the spacer-and-expander will be compressed circumferentially and will urge the sealing-rings outwardly by means of the aforesaid surfaces of said rings outwardly by means of the aforesaid ring-engaging surfaces of said radially-thrusting ring-engaging tabs.
